To all whom it may concern:

Be it known that we, WILLIAM LA HODNY and GUST. C. HOFF, both citizens of the United States, and both residing at Buffalo, in the county of Erie and State of New York, have invented a new, original, and ornamental Design for a Pedestal Mirror, of which the following is a specification, reference being had to the accompanying drawing, forming part thereof:

In said drawing:

We claim:

The ornamental design for a pedestal mirror as shown.

WILLIAM LA HODNY.
GUST. C. HOFF.
